EDWARD W. STIFEL, OF WHEELING, WEST VIRGINIA, ASSIGNOR TO J. L. STIFEL & SONS, INC., OF WHEELING, WEST VIRGINIA, A CORPORATION OF WEST VIRGINIA

DESIGN FOR A TAG

Application filed July 29, 1932. Serial No. 44,484. Term of patent 14 years.

To all whom it may concern:

Be it known that I, EDWARD W. STIFEL, a citizen of the United States, and a resident of Wheeling, in the county of Ohio and State of West Virginia, have invented the new, original, and ornamental Design for a Tag, of which the following is a specification.

Reference is had to the accompanying drawing, forming part thereof, wherein—

I claim:

The ornamental design for a tag substantially as shown.

EDWARD W. STIFEL.
